UNITED STATES PATENT OFFICE.

BENJAMIN J. ANGELL, OF ATTLEBOROUGH, MASSACHUSETTS.

METHOD OF MOUNTING GEMS.

SPECIFICATION forming part of Letters Patent No. 237,669, dated February 15, 1881.

Application filed May 25, 1880. (No model.)

To all whom it may concern:

Be it known that I, BENJAMIN J. ANGELL, of Attleborough, in the county of Bristol and State of Massachusetts, have invented a new and Improved Method of Mounting Gems; and I do hereby declare that the following specification, taken in connection with the accompanying drawings, forming a part of the same, is a full, clear, and exact description thereof.

My invention relates to the mounting of a stone in a setting or shell of metal for the face of a button, stud, or other article; and it consists in preparing the metal shell or setting, as hereinafter described, and forcing the stone into the same, so that the said setting will exactly fit the stone.

The object of my invention is to mount stones economically and in such a manner that the settings will fit the stones, regardless of slight variations in the latter, and also in such a manner that no substance will need to be interposed between the stone and the back member to hold the former in place.

My improved method is adapted to mounting real or imitation stones of rectangular, circular, oval, or other shape; but for the purpose of illustrating my invention I have chosen a rectangular stone having a flat face.

Referring to the accompanying drawings, Figure 1 shows, in perspective, a metal shell or setting. Fig. 2 represents, in perspective, a stone adapted to be mounted in said shell. Fig. 3 shows, in vertical section, the stone and setting in position to be combined. Fig. 4 represents, in section, the relative positions of the stone and setting after they are combined. Fig. 5 shows a top view of the mounted stone and its setting. Fig. 6 represents, in perspective, a metal back member adapted to combine with the metal shell or setting and retain the stone in position; and Fig. 7 represents, in section, the stone, setting, and back member combined.

The method heretofore usually employed in mounting stones has been to provide the face of the shell in which the stone is to be set with an opening or perforation of the size required to admit and exhibit, to a desired extent, stones of a definite shape and size, then to insert the stone by hand and secure it in position by a back member. This method has

been unsatisfactory, and at times comparatively expensive, for the following reasons: Stones of a definite size and style, as they come from the lapidary, vary slightly in shape, area, and thickness, and are often unequally and unevenly ground. A definite size and regularly-shaped opening in the shell, therefore, will exactly fit a stone in but few instances. If a stone is a trifle large for the opening in the shell, or is unevenly dressed, the shell has to be cut or filed or the stone ground off; and if a stone is too small to perfectly fit the perforation in the shell, or is unevenly ground, a space will be left between some portion of the shell and stone, thereby producing an unsightly appearance. Variations in the area of regularly-shaped stones cause them to protrude unequally from the setting, and a variation in thickness, area, or shape often necessitates the interposition of paper or other substance between the stone and back member, in order that the former shall be tightly held in position. In mounting stones by the common method, therefore, a desirable appearance is not usually obtained, and more or less fitting and "papering" are required to be done.

My improved method of mounting stones obviates these objectionable features and secures in each instance a desirable appearance and a securely-mounted stone.

Referring to the drawings, A represents the metal shell or setting, which has been swaged into shape and perforated by properly-formed tools, and B is a stone adapted to be mounted in said shell. The area of the perforation *a* in the shell A is less than the area of the stone B in a plane (*xx*, Fig. 4) passing through the points of contact between the edges *a'* of the perforation and the sides *b* of the stone after it has been fully set. C is a back member, adapted to be combined with the shell and stone to hold the latter in place after it is mounted.

The operation of mounting is preferably performed in a press having a die suited to receive and hold the shell or setting and a follower adapted to force the stone and back member into said shell, the said operation being substantially as follows: The shell A is placed in the die of the press, the stone B is placed in the shell, the two parts occupying

relative positions about as shown in Fig. 3, and the back member C is placed upon the stone. The follower of the press is now made to descend and force the stone and back member into the shell, the said parts, when combined, occupying relative positions about as shown in Fig. 7. By this operation the perforation a is expanded and its edges a' are made to assume the contour of the stone and fit the same exactly, as shown in Fig. 5, while the rim c of the back member C comes into contact with the rim of the shell, and the stone is held in position. In order to avoid the possibility of a separation of the parts after they are combined, the whole, or a portion of the outer surface of the rim c of the back member C or the inner surface of the rim of the shell may be coated with solder and acid, or equivalent material, before the said back member is forced into the shell, and the parts be secured by heat after the mounting.

Although, as shown in Fig. 1, the edges a' of the shell are unbroken, yet they may be wholly or partially serrated, if desired, it only being necessary that the distance between the projecting points of such serrated edges before the stone is mounted be less than the area of the stone in a plane passing through said points after the stone is fully mounted.

Although I prefer to combine the stone and back member with the shell at one operation, I am aware that the stone may be forced into

the shell and the back member afterward be combined therewith.

Having described my invention, what I claim, 35 and desire to secure by Letters Patent, is—

1. The improved method herein described of combining a stone with a setting having a continuous rim and a perforated face, which consists in inserting the stone from the back 40 of the setting and forcing said stone into the perforated face of said setting, thereby expanding the perforation and causing the setting to fit the stone, substantially as set forth.

2. The improved method herein described 45 of mounting a stone in its setting, which consists in forcing the stone and a back member into a shell or setting adapted to said parts, as described, whereby the perforated face of the setting is expanded and made to fit the 50 stone, and said stone is held in position, substantially as set forth.

3. The improved method herein described of mounting and securing a stone in its setting, which consists in providing the rim of the 55 setting or the back member with soldering material, then forcing the stone and back member into the setting, as described, and heating the setting and back member to unite them, substantially as set forth.

BENJAMIN J. ANGELL.
